 tion of New York

Application September 23, 1948, Serial No. 50,856

9 Claims. (Cl. 34—58)

1

This invention relates to apparatus for drying solid materials such as various types of salt or other crystalline or granular materials.

It is an object of this invention to provide apparatus of the aforementioned type which will remove minor quantities of liquid from solid materials in a much more efficient, economical and simple manner than has been heretofore known in the art.

In the field of drying various salts, such as sodium chloride, ammonium phosphate and the like, there is a great need for an economical, compact machine or device which will completely dry the salt from its initial slurry state, wherein a large percentage of water is mixed with the solid material, in a rapid and efficient manner. While centrifugal separators satisfactorily remove the major portion of the liquid from a slurry, there is a residual film of liquid on the solid particles which cannot be removed by centrifugal action. Accordingly, it is the general object of the present invention to provide means to completely dry solid materials containing minor quantities of liquid and which, therefore, is effective to complete the drying of slurries or the like which have been partially dried by other forms of driers, such as a centrifugal.

In applicant's copending application on "Rotary Drier," Serial No. 49,613, filed September 16, 1948, is disclosed a machine for completing the drying of a slurry which has been partially dried by prior treatment. That machine is adapted by the action of hot gases to complete the drying of material containing ten per cent (10%) of liquid or less and is readily adjusted to remove varying quantities of moisture. It is found, however, that in some cases, particularly when the preliminary drier is of the centrifugal type, the moisture content of material is only two per cent (2%) or less. In such cases, the final drying by hot gases may be effected in a very brief period. Accordingly, it is the general object of the present invention to provide an improved and simplified machine for drying materials which contain approximately two per cent (2%) moisture or less by the action of hot gases.

It is a further object of this invention to provide in apparatus of the aforementioned type a more or less cylindrical chute into which partially dried solid materials are rotatably and axially fed while heated air is passed therethrough so as to dry the material as it moves along a helical path from the inlet end to the discharge end thereof.

It is a further object of this invention to provide a chute of the aforementioned type having

2

a lining of water repellent and abrasive and heat resistant material so that the solid materials discharged into said chute will not adhere to the walls thereof.

5 It is a further object of this invention to provide apparatus of the aforementioned type which includes an improved stationary chute adapted to be directly associated with a centrifugal drier in such a manner that the partially dried material is fed into the chute and moved helically therethrough as the result of the speed of discharge of the material from the rapidly rotating centrifugal.

10 It is a still further object of this invention to provide, in a chute of the aforementioned type, means for engaging and reducing the speed of the material discharged into the chute from the partial drying device prior to the engagement of the material with the peripheral wall of the chute, so as to prevent any abrasive wearing of the peripheral wall lining.

15 It is a still further object of this invention to provide, in conjunction with deflecting means of the aforementioned type, a coolant jacket adapted to contain a coolant for maintaining the deflecting means at a predetermined temperature, so as to eliminate any tendency for the material discharged into said chute to dry on and adhere to said deflecting means.

20 It is a still further object of this invention to provide a peripheral wall for a chute of the aforementioned type which is provided with openings through which heated gas may pass from exteriorly of said chute so as to dry the material moving through the chute and so as to aid the axial movement of the material from the inlet end to the discharge end of the chute.

25 These and other objects of this invention will become apparent from the following detailed description taken in conjunction with the accompanying drawings, in which:

30 Figure 1 is a sectional view of one form of final drying apparatus of this invention and means for axially and centrifugally feeding solid materials thereto;

35 Figure 2 is a sectional view of the structure illustrated in Figure 1 taken along the line 2—2 thereof;

40 Figure 3 is a sectional view of a further embodiment of the invention illustrating a complete drying machine including a centrifugal drier associated with the preferred form of final drying device; and

45 Figure 4 is an end elevational view of the structure illustrated in Figure 3 with parts broken away in section for purposes of clarity.

Referring now to the embodiment of the invention illustrated in Figures 1 and 2, it will be seen that a feeding mechanism 5 is provided for axially and centrifugally feeding solid materials from a suitable partial drying device into a frusto-conically shaped chute 7. The chute 7 is supported by a suitable framework 8 and is surrounded by a housing 9. The feeding device 5 includes a conduit 10 having a feed screw 11 therein which axially feeds the material from the 10 partial drying device through the conduit.

In order to impart a rotary and axial motion to the material being discharged from the feeding mechanism into the chute 7, a rotating sleeve 13, having a frusto-conical inner wall 14 and fins 15, is rotatably supported on the framework 8. The outer end of the sleeve 13 overlaps the discharge end of the conduit 10 so that the solid material will be fed from the conduit into the sleeve 13. The sleeve 13 is rotatably driven at high speed by any suitable means such as a roller 19 which is connected, in a conventional manner, with suitable driving means and which frictionally engages an annular ring or track 21 on outer periphery of the sleeve 13. The material, therefore, will be moved from the partial drying device by the feed mechanism 5 and will be discharged from the sleeve 13 into one end of the chute 7 with a high velocity tangentially of sleeve 13 which will cause the material to slide through the chute in a helical path.

The chute 7 is formed with a frusto-conical peripheral wall 25 which is smaller in diameter at the inlet end of the chute than at the opposed discharge end thereof. The peripheral wall 25 is made up of a plurality of axially overlapping, radially spaced, concentric rings 27, such as illustrated and described in applicant's above-mentioned copending application, Serial No. 49,613. The rings 27 are connected together by means of a plurality of circumferentially spaced securing members 29 which have the inner faces thereof axially stepped at 31 so that the rings 27 can be secured thereto in the aforementioned overlapping and spaced relationship by means of countersunk screws 33. The securing members 29 thus support and secure the rings in the aforementioned relationship so as to provide air passageways 35 between the overlapping portions thereof through which gases may pass for drying the material which moves through the chute 7. It will be noted that the air passageways 35 extend substantially parallel to the axis of the drum and face the outlet end thereof.

The chute housing 9 is provided with a suitable gas inlet passageway or conduit 37 (Figure 2), through which heated gas is conducted into the space within the housing around the outer periphery of the chute 7. The heated gas then passes through the air passageways 35 in the peripheral wall of the chute 7 so as to dry the material moving therethrough. A suitable gas outlet conduit or passageway 39 is provided in the upper portion of the housing 9 so that the gas which passes into the chute 7 will flow out of the open end thereof into the outlet passageway 39. The gas may then be reheated and recirculated, so as to reduce the user's power and fuel costs. The housing 9 likewise is provided, adjacent the outlet end of the chute 7, with a material discharge chute or passageway 41 into which the dried material from the chute is discharged.

In operation, the partially dried material from the partial drying device is fed into the inlet end

of the chute 7 by means of the feed mechanism 5, previously described. The material will then engage the chute peripheral wall 25 and slide helically at high speed through the chute and be held in contact with the walls by centrifugal force until it reaches the discharge end of the chute, even though the chute, itself, is not rotated. The heated gas passes through the air passageways 35 and the material moving through the chute. In this way heated gas is passed through the material throughout its entire movement through the chute and the material will be completely dried by the time it reaches the outlet end of the chute and is discharged into the material discharge passageway 41. The flow of the gases through the wall passageways 35 and the frusto-conical shape of the inner wall 14 of the rotating sleeve 13 aid in imparting the axial component of movement to the material fed into and moving through the chute.

By forming the chute peripheral wall in the aforementioned manner and by feeding the material helically through the chute at high speed, the material will slide along the inner wall of the chute in a thin layer without sticking to the wall surface, and the flow of hot gas through the rapidly moving thin layer will effect complete drying of the material by the time it reaches the discharge end of the chute 7. Furthermore, by overlapping and spacing the peripheral wall, rings 27, the air spaces through which the heat passes will not become clogged by the material moving through the chute. It will thus be seen that the drying device is especially simple in construction and efficient and economical in operation. It is a relatively simple matter to provide means, such as the feeder 5, for giving the material the high speed of feeding movement necessary to carry the material through the chute, and this greatly reduces the cost and complexity of the machine by making it unnecessary to rotate the chute. Even the feeding device may be omitted if the drier is used to complete the drying of material discharged from a centrifugal separator of the continuous discharge type, since in that case the material discharged from the centrifugal already has the requisite velocity. In this case, the rotating drum or basket of the centrifugal may occupy the position of the sleeve 13, in the manner set forth more fully hereinafter.

In the embodiment illustrated in Figures 3 and 4, a centrifugal separator 45 of known construction is illustrated for partially drying the solid materials and feeding them into a slightly modified form drier with the desired high tangential velocity. With the centrifugal separator of this device, a slurry of material containing a large percentage of liquid is fed into an inlet tube or conduit 49. The slurry flows through the tube 49 into a funnel-shaped member 51 which discharges it into a rotating basket or housing 53 having a plurality of openings 55 in the peripheral wall thereof through which liquid may be discharged. A peripheral screen 57 is secured to the housing 53 inwardly of the peripheral wall thereof so as to prevent the solid material from passing through the housing openings 55. The housing 53 is rotatably driven in any suitable manner through a hollow shaft 57 so that the majority of the liquid in the slurry will be centrifugally discharged and separated from the solid material through the openings 55. The centrifugal separator will, however, not remove all of the liquid from the solid material. The partially dried material is axially discharged more

or less continuously from the open end of the housing 53 past a chamfered lip 58, by means of a reciprocating disk plate 59 which is axially reciprocated in any suitable manner by a shaft 61 which extends through the rotatable shaft 57, a wash water inlet conduit 62 has one end extending into the centrifugal drier for use in cleaning the same.

The chute 47 and centrifugal separator 45 are supported on a suitable stand and framework 63, and housings 64 and 65 enclose the chute 47 and separator 45. The chute 47 is of a generally frusto-conical shape and has its small diameter end disposed adjacent to the centrifugal separator 45 so as to receive the material discharged therefrom and aid in imparting an axial component of motion to the material. The chute 47 is provided with a peripheral wall 66 which is made up of a pair of frusto-conical shaped bands or rings 67 which have their adjacent ends secured in an axially overlapping and radially spaced relationship so as to provide an air passageway 69 between the overlapping portions thereof. If the machine is to be used in drying such materials as salt, it has been found that the relatively high temperature of the drum walls tends to dry out a film of solid material which adheres tenaciously to the drum walls and so increase the coefficient of friction of the walls that material will not slide freely thereon. Serious clogging of the machine may result in such cases. Accordingly, the inner surface of each of hoop-like members 67 is lined with an abrasive-resistant, water repellent material 71, which will withstand at least 350° F. of heat. The preferred lining material for this purpose is polytetrafluoroethylene, a plastic which is sold under the trade name "Teflon," but other suitable materials, such as glass, which have the aforementioned characteristics may be used. Suitable means, such as screws or rivets 70, are employed to secure the lining to the bands or rings 67.

The inlet or small diameter end of the chute 47 is supported on the framework 63 by means of an annular member 72. The annular member 72 includes a pair of spaced ring portions 73 and 73' which are interconnected by means of a plurality of circumferentially spaced ribs 74. The ring portion 73' is connected to the framework 63 and the ring portion 73 is connected to the inner end of the chute peripheral wall 66 so that a plurality of air passageways is provided which connect the inlet end of the chute with the space between the outer periphery of the chute and the housing 64, as will hereinafter appear. The outer or discharge end of the chute 47 is supported on and secured to the housing 64 by a plurality of circumferentially spaced angle brackets 84, so that air passageways are provided around the discharge end of the chute which communicate with the space between the chute 47 and housing 64.

Since centrifugal separators must operate at very high speeds to remove the maximum amount of liquid, the speed at which the material is discharged by the centrifugal is not only higher than necessary but is such as to cause undesirable wear of the lining material 71. Accordingly, when such linings are required in a machine of the type shown in Figure 3, it is desirable to provide means for reducing the tangential speed of movement of the material as it leaves the centrifugal. In the machine of Figure 3, this is accomplished by a deflector 75 positioned in the inlet end of the chute adjacent the discharge end 75

of the centrifugal separator 45. The deflector 75 is in the form of an annular ring or hoop 76 having an outwardly projecting circumferential flange 77 which is connected to the annular member 72. The annular deflector ring 76 is preferably made of a material such as stainless steel, and has a coolant jacket 79 surrounding the outer periphery thereof and adapted to contain a coolant for maintaining it at a predetermined temperature which will prevent the solid material from adhering thereto, as will be hereinafter pointed out a suitable coolant conduit 80 is provided, through which coolant can flow to the water jacket. The material which is helically discharged from the centrifugal separator 45 will, therefore, first engage the inner surface of the annular ring 75 before engaging the lining 71 on the peripheral wall 66 of the chute 47. The speed as well as the impact of the solid material against the lining 71 will, therefore, be reduced and will reduce abrasive wearing of the lining.

In order to dry the solid material as it passes from the inlet end to the discharge end of the chute 47, an inlet passage or conduit 81 (Figure 4) is provided in the housing 64 through which heated gas is passed into the space between the peripheral wall of the chute and the housing. The gas, which is heated to approximately 350° F., will then pass through the passageways 69 between the overlapping portions of the chute's peripheral wall rings 67 and through an annular passageway 83 between the deflector 75 and the centrifugal separator 45, as well as through passageways 85 provided between the inlet end of the chute's peripheral wall and its supporting annular member 72. Also, gas will flow through the passageways at the discharge end of the chute so that heated gas is passed through the solid material at several points as the latter moves through the chute. It will be noted that the heated gas flows into and through the chute substantially parallel to the axis thereof and, therefore, imparts axial movement to the material in the chute, thus aiding in moving the latter axially from the inlet end to the discharge end of the chute. Thus, the centrifugal drier chamfered lip 58, the frusto-conical shape of the chute 47 and the flow of the gas all aid in imparting the axial component of movement to the material. The gas, after passing through the material within the chute 47, flows out of the discharge end of the chute and into an outlet conduit 89. In this way, a continuous flow of heated gas passes through the air passageways in the chute so as to completely dry the material passing through the chute.

In operation, the partially dried material is tangentially and axially discharged from the centrifugal separator 45 into the inlet end of the chute 47, as previously described. The material will first engage the inner periphery of the annular deflecting ring 75 and will then engage the peripheral wall of the chute and travel along an expanding helical path toward the chute discharge end. The deflecting ring 75 is maintained, by means of the coolant in the coolant jacket 79, at a temperature which is high enough to prevent condensation and low enough to prevent drying of the material thereon which otherwise would be caused by the heat in the chute. The material, after engaging and being slowed up by the annular ring 75, slides helically through the chute without causing abrasive wear on the lining 71. Due to the aforementioned characteristics of the lining 71, the material will not adhere thereto but

will move rapidly through the chute in a thin layer in contact with the walls while the heated gas is passed therethrough so as to completely dry it by the time it is discharged. The material is then discharged from the chute into a discharge passageway or chute 39 in the housing 34 and the dried material, such as salt, is ready for its ultimate use.

The centrifugal separator 45, illustrated in Figure 3, is of previously known construction, but it will be understood that any form of centrifugal separator may be employed with either form of the invention so long as it is capable of discharging the partially dried material continuously over the entire periphery of the open end of the rotating drum or basket.

It will, of course, be appreciated that while only the chute illustrated in Figures 3 and 4 has a lining of water repellent and abrasive and heat resistant material, the chute illustrated in Figures 1 and 2 may be provided with such a lining and preferably is when the material being dried is salt. It furthermore will be appreciated that while the chutes and the centrifugal drier are illustrated in the drawing as being disposed on a horizontal axis, they could be vertically mounted and discharge either upwardly or downwardly without departing from the spirit and scope of this invention. Likewise, the forms of chutes illustrated in Figure 1 may be substituted for that in Figure 3, or vice versa.

What is claimed is:

1. Apparatus for removing liquid from moist solid material, comprising a stationary chute having a surface which is circular in cross section over which said material may helically slide, said chute having openings in said surface, said surface being formed of a material which is water repellent and resistant to heat and abrasion, and means for directing heated gas through said openings and the material moving thereover.

2. Apparatus for removing liquid from solid materials, comprising a stationary chute which is circular in cross section and receives on its inner surface, through an opening in one end thereof materials discharged at high speed tangentially from the basket of a centrifugal separator and cause such materials to follow a helical path through said chute in contact with said chute surface, and means for directing a heated gas through the material as it slides helically through said chute in contact with the inner wall thereof, said chute having a lining of material which is water repellent and abrasive and heat resistant on the inner surface of its wall.

3. Apparatus for removing moisture from solid materials, including a stationary chute having a peripheral wall which is circular in cross section, a rotating feeding means adjacent one end of said chute for feeding partially dried material into one end of said chute at a high speed in a circumferential direction whereby the said material slides helically along and in contact with the chute peripheral wall from the inlet end to the opposite end thereof, said means being circular in cross section and terminating adjacent one end of the peripheral wall of said chute, passageways in said chute wall through which gas can flow into said chute from exteriorly thereof, and means for directing heated gases from exteriorly of said chute through said passageways so as to dry the material moving from the inlet end to the discharge end of said chute.

4. Apparatus for removing moisture from solid materials, including a stationary chute having a

75 peripheral wall which is circular in cross section, mechanism for feeding partially dried material into one end of said chute with a rotary component of motion and sufficient velocity to cause the material to slide around the walls of the chute in contact therewith until it is discharged from the other end, a lining on the inner surface of the peripheral wall of said chute of material which is water repellent and abrasive and heat resistant, openings in said chute through which gas may flow from exteriorly of said chute, and a baffle element adjacent the inlet end of said chute adapted to be engaged by the material fed into said chute prior to the engagement of said material with the peripheral wall lining thereof.

5. Apparatus for removing moisture from solid materials, including a stationary chute having a peripheral wall which is circular in cross section, mechanism for feeding material into one end of said chute with a rotary component of motion and sufficient velocity to cause the material to slide around the walls of the chute in contact therewith until it is discharged from the other end, a lining on the inner surface of the peripheral wall of said chute of material which is water repellent and abrasive and heat resistant, openings in said chute through which gas may flow from exteriorly of said chute, an annular ring positioned in the inlet end of said chute for engaging and slowing down the material fed into said chute prior to the engagement of the material with said chute peripheral wall lining, and a coolant jacket surrounding said annular ring and adapted to contain a coolant for maintaining said annular ring at a predetermined temperature wherein said material will not stick to said ring.

40 6. In apparatus for removing moisture from solid materials, a stationary chute having a peripheral wall which is circular in cross section and into one end of which partially dried material may be fed so as to cause it to slide around the wall of the chute and in contact therewith until it is discharged from the opposite end, a lining on the inner surface of the peripheral wall of said chute of material which is water repellent and abrasive and heat resistant, said chute wall and lining having openings therein which extend axially of said chute through which heated gases may flow from exteriorly of the chute so as to dry material moving through the chute, and a baffle element adjacent the inlet end of the chute adapted to be engaged by the material fed into said chute prior to the engagement of said material with the peripheral wall lining thereof.

55 7. Apparatus for removing moisture from solid materials including a stationary chute having a peripheral wall which is circular in cross-section, mechanism for feeding partially dried material into one end of said chute at a high speed in a circumferential direction whereby said material slides helically along and in contact with the chute peripheral wall from the inlet end to the opposite end thereof, passageways in said chute wall through which gas can flow into said chute from exteriorly thereof, the inner surface of said chute wall being formed of a material which is water-repellent and resistant to heat and abrasion, and means for directing heated gases from exteriorly of said chute through said passageways so as to dry the material moving from the inlet end to the discharge end of said chute.

8. Apparatus for removing moisture from solid materials including a horizontally disposed stationary chute having a peripheral wall which is

circular in cross-section, mechanism for feeding partially dried material into one end of said chute at a high speed in a circumferential direction whereby said material slides helically along and in contact with the chute peripheral wall from the inlet end to the opposite end thereof, passageways in said chute wall through which gas can flow into said chute from exteriorly thereof, and means for directing heated gases from exteriorly of said chute through said passageways so as to dry the material moving from the inlet end to the discharge end of said chute.

9. Apparatus for removing moisture from solid materials including a horizontally disposed stationary chute having a peripheral wall which is circular in cross-section, mechanism for feeding partially dried material into one end of said chute at a high speed in a circumferential direction whereby said material slides helically along and in contact with the chute peripheral wall from the inlet end to the opposite end thereof, passageways in said chute wall through which gas can flow into said chute from exteriorly thereof, the inner surface of said chute wall being formed of a material which is water-repellent and resistant to heat and abrasion, and means for directing heated gases from exteriorly of said chute through

said passageways so as to dry the material moving from the inlet end to the discharge end of said chute.
